(57) **CLAIM**

The ornamental design for an industrial camera as shown and described.

DESCRIPTION

FIG. 1 is a bottom view of an industrial camera of our new design.

FIG. 2 is a top view thereof.

FIG. 3 is a left side view thereof.

FIG. 4 is a right side view thereof.

FIG. 5 is an end view thereof.

FIG. 6 is an opposite end view thereof.

FIG. 7 is a perspective bottom view thereof; and,

FIG. 8 is a perspective top view thereof.
